UNITED STATES PATENT OFFICE.

ALFRED F. MASURY AND CHARLES FROESCH, OF NEW YORK, N. Y., ASSIGNEES TO
INTERNATIONAL MOTOR COMPANY, OF NEW YORK, N. Y., A CORPORATION OF DEL-
AWARE.

AIR-COOLED ENGINE.

Application filed December 22, 1925. Serial No. 77,159.

This invention relates broadly to enclosures for internal combustion engines and more particularly, in an air cooled engine, to the structure by which the current of cooling air is brought into and removed from contact with the walls of the engine. The object of the present invention is to provide an enclosure for the engine which may be availed of, if desired, to facilitate the admission and escape of the cooling air and which embodies certain novel features having to do with a simplification of the enclosure in the interest of ease of manufacture and convenience in use. To this end the 5 cam shaft which actuates the gears is disposed within a housing utilized as an element of the engine enclosure and from this housing there extends in a generally downward and outward direction, side walls of 10 the enclosure to be supported by a transverse floor defining the bottom of the enclosure. This floor is preferably formed integral with the engine crank case and extends forwardly of the engine to support a 15 front end member which may be formed with a forwardly directed opening through which air enters or is drawn by a fan disposed therewithin. While the invention is not limited in its use to a conveyance, such 20 as a motor vehicle or airship, it will be found particularly applicable to self-propelled vehicles. These and other objects of 25 the invention and the means for their attainment will be more apparent from the following detailed description of a preferred embodiment thereof which is illustrated in the accompanying drawings, and in which:

Figure 1 is a view in side elevation showing the engine and the enclosure therefor according to the present invention, the side 40 walls of the enclosure being removed in the interest of clearness.

Figure 2 is a transverse, vertical sectional view taken through one of the cylinders and 45 showing the enclosure forming the passage for the cooling air and the means of egress of the air after a heat interchange has taken place.

Figure 3 is a plan view of the engine and 50 enclosure, looking from above, and showing the path taken by the air from the time it enters the enclosure until it is emitted therefrom.

While the invention has been illustrated

as applied to an air cooled internal combustion engine it will be apparent as the description proceeds that certain features thereof are applicable in situations other than when air is used as the cooling medium. The engine, which may be of any desired 55 type, is illustrated as comprising four spaced cylinders *a* having formed thereon cooling fins *a'* and supported from a common crank case *b*. The crank case may be supported 60 as by the arms or brackets *b'* from the longitudinal side members *c* of the vehicle frame. The cam shaft *d* which actuates the valves *e* of the respective cylinders is located above 65 the bank of cylinders and is disposed within a housing *f* containing lubricant. The housing *f* is utilized as a part of the enclosure 70 serving, in connection with an air cooled engine, as the passage for the cooling air. To this end it is disposed sufficiently above 75 the engine to afford an air passage *f'* thereabove and is formed with flanges *f''* on either side to which the side walls *g* may be hinged or otherwise secured. These side walls extend generally downwardly and outwardly 80 to engage with or unite with the floor of the air passage. This floor is preferably a flange *b''* formed integral with the crank case *b*, below which the carburetor *h* and the exhaust pipe *i* are disposed, and which extends forwardly of the engine as at *b''x* to 85 support the front end *j* of the enclosure.

The cooling air is drawn into the enclosure through a screened opening *j'* either by the forward motion of the conveyance or by the action of a fan *k* within a housing *k'* 90 whereof the inlet *k''* faces the opening *j'* and is directed into one side of the enclosure through an inlet *k''* formed by a baffle *l*. From one side of the bank of cylinders the air flows to the other side, as shown by the 95 arrows, around the individual cylinders and is directed into contact with the cooling fins and cylinder walls by deflectors *m*, *n*, where a heat interchange takes place. The deflector *m* comprises a section of pyramidal half section disposed with the acute edge in the direction of the approaching air to deflect it upwardly and against the cylinder. The warmed air is permitted to escape through apertures or louvers *g'* formed in the one 100 wall *g*. It is to be noted that the air enters the enclosure and first contacts with the cylinders on the side opposite to the exhaust

manifold i' so that no heat is taken up by the air prior to its contact with the cylinders.

The housing f for the cam shaft may take various forms. A preferred construction is illustrated in the drawings and comprise a four sided box or tube supported at the front end by the housing o containing the driving connection for the fan and cam shaft d and at the rear end in any convenient manner,

10 say by a transverse partition p serving as the rear wall of the engine enclosure. The valve stems enter the housing for engagement by the cams through spring guides q threaded into openings f^3 in the bottom 15 and sealed against escape of lubricant by telescoping caps r engaging the respective spring seats s on the top of the valve stems.

By the construction described a particularly efficient cooling of an internal combustion 20 engine is effected and the enclosure or air channel within which the engine is disposed is simplified by taking advantage of auxiliary structures of the engine.

Various modifications may be made in the 25 arrangement and configuration of the component elements going to make up the device as a whole and are to be deemed within the spirit and scope of the invention as set out in the appended claims.

30 What we claim is:

1. In combination, an internal combustion engine comprising spaced cylinders having an exhaust manifold along one side, an enclosure for the engine formed with an opening 35 in the front end and louvers on the side adjacent the exhaust manifold, a fan disposed in front of the engine and a fan housing having an inlet adjacent the opening in the enclosure and an outlet to deflect the air 40 from the fan to the side of the engine away from the exhaust manifold.

2. In combination, an internal combustion engine comprising spaced cylinders having an exhaust manifold along one side, a hood for the engine formed with an opening in the front end and louvers on the side adjacent the exhaust manifold, a transverse horizontal floor integral with the crank case upon which the hood is supported at the outer edges thereof, a fan disposed in front of the engine and a fan housing having an inlet adjacent the opening in the hood and

an outlet to deflect the air from the fan to the side of the engine away from the exhaust manifold.

55

3. In combination an internal combustion engine comprising spaced cylinders having an exhaust manifold along one side, a hood for the engine formed with an opening in the front end and louvers on the side adjacent the exhaust manifold, a transverse horizontal floor integral with the crank case upon which the hood is supported at the outer edges thereof, a fan disposed in front of the engine, a fan housing having an inlet 65 adjacent the opening in the hood and an outlet to deflect the air from the fan to the side of the engine away from the exhaust manifold, and deflectors carried with the crank case to deflect the air against the cylinder.

65

4. The combination with an internal combustion engine and a cam shaft, of an enclosure for the engine comprising a housing for the cam shaft, a horizontal flange along either side of the engine and side walls connected to the housing and extending to the flanges.

70

5. The combination with an internal combustion engine including a crank case and having a cam shaft, of an enclosure for the engine comprising a housing for the cam shaft, a horizontal flange formed along both sides and front of the crank case, side walls connected with the housing and extending 85 to the flange, one of said side walls being formed with an opening and a front end member having an opening and supported on the flange, means to induce a flow of air into the enclosure through the opening, and 90 means to direct the air to one side of the engine.

85

6. In combination, a housing for a cam shaft comprising a four walled tube whereof the bottom wall is formed with a plurality of 95 apertures, cylindrical valve spring guides disposed within the apertures, and caps carried in telescoping engagement with the guides.

90

This specification signed this 9th day of 100 December A. D. 1925.

ALFRED F. MASURY,
CHARLES FROESCH.
